UNITED STATES PATENT OFFICE.

GEORGE W. OAKES, OF BRITT, IOWA.

BROODER.

Application filed February 21, 1928. Serial No. 255,967.

The present invention relates to improvements in brooders and has for its principal object to provide a structure to be used in raising young fowl, wherein the same includes the provision of a heat distributing water header that is arranged beneath a hover, a water heating chamber being in communication with the header for heating the water and causing the same to circulate through the header and the chamber.

A further object is to provide a brooder which will eliminate any possibility of gases from the heating unit entering the brooder thus rendering the air pure, additional means being provided for regulating the heat whereby to maintain an even temperature.

A further object is to provide a brooder of the above mentioned character which is simple in construction, inexpensive, strong and durable and further well adapted to the purpose for which it is designed.

Other objects and advantages of the invention will become apparent during the course of the following description when taken in connection with the accompanying drawings.

In the accompanying drawings wherein like reference characters indicate corresponding parts throughout the several views:

30 Figure 1 is a side elevation of the brooder embodying my invention.

Figure 2 is a top plan view thereof, the apex portion of the conical hover being broken away to illustrate the water header in 35 top plan.

Figure 3 is a vertical sectional view, parts of the invention being shown in elevation.

Figure 4 is a sectional view taken substantially on the line 4—4 of Figure 2, and

40 Figure 5 is a vertical section taken substantially on the line 5—5 of Figure 3.

In the drawings wherein for the purpose of illustration is shown the preferred embodiment of my invention, the numeral 1 45 designates generally my improved brooder, the same comprising a conical shaped hover 2 that is provided at its lower edge with a depending annular flange 3. A plurality of supporting legs 4 are secured adjacent their upper ends to the depending flange 3 of the hover 2 at spaced intervals. The lower end of each leg member is formed with a laterally extending ground engaging foot 5, while the upper extremity of each leg member is disposed outwardly as at 6, and the outer end

of the laterally extending portion 6 is formed with a loop 7.

A curtain 8 surrounds the leg members 4 and is secured at its upper edge to a wire ring 9 and this ring is disposed within the alined loops 7. The purpose of the curtain is to provide a means for keeping out the draft and the supporting legs 4 space the hover from the ground as is clearly shown in Figures 3 and 4 of the drawings. 65 The brooder further includes the provision of a floor 10 that is supported in spaced relation with respect to the ground by means of the angular brackets 11 that are secured to the leg members 4 adjacent the ground 70 engaging feet 5. A central support 12 is provided for the floor 10 as clearly shown in Figure 3.

Forming a salient part of the present invention is the cylindrical water header 13 75 that is arranged vertically and centrally in the brooder, the same being closed at its respective ends and secured on the floor 10 in any appropriate manner. This cylindrical water header is provided with a series of 80 vertical flues 14 that extend for the full length of the header and the bottom 10 is formed with the openings 15 for communication with the lower inlet ends of the air flues 14 as clearly shown in Figure 3. The 85 top of the header is spaced from the apex portion of the conical hover 2 so that the heated air emitted from the open upper ends of the air flues 14 will be free to circulate in the upper portion of the hover and thence 90 be directed downwardly as will be herein-after more fully described.

A water supply tank 16 is supported exteriorly of the brooder on the support 17 at a height such as to arrange the supply 95 tank above the header 13, and a supply pipe 18 extends from the lower portion of this supply tank, through the upper portion of the hover 2 into the header 13 as illustrated very clearly in Figure 3. This will afford 100 a means whereby the header 13 will be filled with water.

The invention further comprehends the provision of a water heating chamber 19 that is arranged exteriorly of the hover and this 105 chamber is provided with a central flue 20. A lamp 21 is arranged beneath the chamber 19 for heating the same. Communication between the chamber 19 and the water header 13 is provided by means of the water 110

circulating pipes 22 and 23, respectively, and the manner in which such communication is afforded is shown very clearly in Figure 3 of the drawings.

5 For the purpose of regulating the heat, there is provided a thermostatically operated damper, the same including a bracket 24 that is secured on the inside of the hover 2 and arranged on this bracket is the frame 25 10 within which is mounted the thermostat or wafer 26. An elongated rod 27 is pivotally secured at its inner end to the bracket 24, the rod extending through the frame and through a suitable opening 28 provided 15 therefor in the hover 2. This rod 27 is operatively associated with the wafer 26 and the outer end of the rod carries a damper plate 29 for cooperation with the upper end of the flue 20 so that when a predetermined 20 temperature is reached, the thermostat or wafer 26 will expand, causing the rod 27 to swing downwardly on its pivot and move the damper plate 29 into engagement with the upper end of the flue 20 for obvious 25 purposes. In this manner, an even temperature may be maintained.

By spacing the floor 10 from the ground an air passage is provided whereby air may enter the flues 14 in the water header 14 and 30 by provision of the chamber 19, the water in the header 13 will circulate through the heating chamber and will be heated, thus heating the air that passes upwardly through the flues 14 and such heated air will be deflected downwardly by the hover for keeping the interior of the brooder warm. The curtain 8 will prevent any draft from entering the brooder.

It will thus be seen from the foregoing 40 description, that I have provided a brooder which will at all times be positive and efficient in carrying out the purposes for which it is designed, and by arranging the heating unit exteriorly of the hover, no gases can 45 enter the brooder, and thus only pure air will circulate in the brooder.

While I have shown the preferred embodiment of my invention it is to be understood that minor changes may be made therein 50 without departing from the spirit of the invention and scope of the appended claims.

Having thus described the invention, what I claim as new and desire to secure by Letters Patent is:—

55 1. In a brooder, a hover, supporting legs therefor, a water header arranged centrally beneath the hover, said header being closed at its upper and lower ends and provided with vertical air flues, a water heating chamber, pipes for affording a circulation of the water between the header and the chamber, a heater for the chamber, the bottom of the

water header being spaced from the ground whereby air may enter the lower ends of the vertical flues, and a water supply tank connected to the water header. 65

2. In a brooder, a hover, supporting legs therefor, a floor supported above the ground on said supporting legs, a water header arranged centrally and vertically on said floor, 70 said header being closed at its upper and lower ends and provided with vertical air flues, said floor being formed with air inlet openings for communication with the lower ends of the respective flues, a water heating 75 chamber, pipes for affording circulation of the water between the header and said chamber, and a heater arranged beneath the water chamber.

3. In a brooder, a hover, supporting legs 80 therefor, a floor supported above the ground on said supporting legs, a water header arranged centrally and vertically on said floor said header being closed at its upper and lower ends and provided with vertical air 85 flues, said floor being formed with air inlet openings for communication with the lower ends of the respective flues, a supply tank in communication with the water header, a water heating chamber arranged exteriorly 90 of the hover, pipes for affording a circulation of the water between the header and the heating chamber, and a heater for said heating chamber.

4. In a brooder, a hover, a series of ground 95 engaging supporting legs secured at their upper ends to the lower edge portion of the hover, the upper extremities of the legs being provided with horizontally disposed loops, a curtain surrounding the space between the bottom edge of the hover and the ground, and a curtain supporting ring carried by the upper edge portion of the curtain, said ring being disposed within the loops. 100

5. In a brooder, a hover, supporting legs 105 therefor, a floor spaced from the ground and supported by said legs, a water header arranged centrally upon the floor said header being closed at its upper and lower ends and provided with a series of vertical air flues, 110 the floor being formed with air inlet openings for communication with the lower ends of the respective flues, a water supply tank communicating with said header, a water heating chamber formed with a central heat flue, said heating chamber being arranged exteriorly of the hover, pipes affording a circulation of the water between the header and the chamber, a heater arranged beneath the chamber, and a damper plate for cooperation with the upper end of the heat flue 115 of said heating chamber. 120

In testimony whereof I affix my signature.
GEORGE W. OAKES.
